UNITED STATES PATENT OFFICE

CHARLES F. SCHWENKER, OF SCHENECTADY, NEW YORK, ASSIGNOR TO GENERAL ELECTRIC COMPANY, A CORPORATION OF NEW YORK

CIRCUIT CONTROLLING MECHANISM

Application filed November 1, 1929. Serial No. 404,142.

My invention relates to circuit controlling mechanism, and more particularly to means for effecting the tripping or opening operation of the mechanism.

5 The use of high speed opening mechanism for circuit interrupting apparatus of comparatively large interrupting capacity is well known. It has been found that rupture of the power arc in modern high tension systems 10 requires high speed of separation of the contacts in order that the arc shall not be drawn to excessive length before it is extinguished and in order that the circuit shall be cleared within a cycle or fraction thereof. The performance 15 however, of such high speed opening mechanism is not necessarily uniform due to the fact that the time of separation of the contacts may occur at different parts of the alternating current cycle, the interruption 20 of the arc being more easily accomplished when the current is at or near its zero value in the cycle, and more difficult when it is at or near its maximum value.

It is a principal object of my invention to 25 provide controlling means for causing opening movement of switch contact structure, particularly of the high speed type, at or during the period when the current traversing the contact structure is at a minimum.

30 It is a further object of my invention to provide controlling means for high speed switch operating mechanism which shall release a holding or latching member when the switch is to be opened during the period in 35 which the current traversing the switch is at or near a maximum value, and which shall subsequently actuate a tripping member to cause opening movement of the switch during the subsequent period when the current is at 40 or near a minimum value.

My invention will be more fully set forth in the following description referring to the accompanying drawings, and the features of novelty which characterize my invention will 45 be pointed out with particularity in the claims annexed to and forming a part of this specification.

Referring to the drawings, Fig. 1 is an elevational view in section illustrating circuit 50 controlling mechanism embodying my in-

vention; Fig. 2 is a fragmentary view of apparatus illustrated in Fig. 1 in another position, and Fig. 3 is a graphic illustration of a cycle of alternating current.

In Fig. 1 there is illustrated by way of example high speed circuit interrupting apparatus of the character described and claimed in my Patent No. 1,721,417 of July 16, 1929. The circuit interrupting apparatus comprises a tank 1 and a superstructure 1' within which are disposed the coacting contacts 2 and 3 of the switch structure. The contact structure may be immersed in an insulating fluid 4, such as oil, the contact 3 being stationary and the contact 2 pivotally mounted at 5 for movement relative thereto. In the closed circuit position illustrated, the movable contact 2 is maintained in engagement with its coacting stationary contact 3 by means of a closing spring 6 attached at one end to a fixed point 6' and at its other end to a floating lever 8, as at 9. A dash pot device 7 is likewise connected between the points 9 and 6'. The lever 8 is centrally pivoted at 8' and at its opposite end is connected at 10 to the contact operating rod 11. The pivot 8' in the position illustrated is held stationary by controlling means presently described so that the tension of the closing spring 6 is effective to bias the floating lever 8 and consequently 70 the movable contact 2 in a counter-clockwise direction to maintain the switch contacts closed.

The switch opening spring 12 is secured at one end to a fixed support 13 and at its opposite end to the pivot 8', the spring 12 being under tension in the closed circuit position. It will therefore be apparent that when the forces restraining the pivot 8' in its stationary position are removed, the comparatively 80 strong opening spring 12 will immediately cause clockwise rotation of the floating lever 8 about its end pivot 9 to effect opening movement at high speed of the contact 2. A buffer or shock absorber 12' is provided and arranged to be engaged by the lever 8 as it reaches the open circuit position.

When the switch is to be reclosed, the pivot 8' must be again restrained in its original 85 stationary position, otherwise downward or 100

switch closing movement of the actuating rod 15 results in merely rocking movement of lever 8 about its end pivot 10. When the pivot 8' is held stationary, however, downward movement of the rod 15 rocks the lever 14 pivoted at 14' in a counter-clockwise direction thereby placing the spring 6 under tension. The spring 6, however, is sufficiently strong to thereupon rock the lever 8 in a counter-clockwise direction about the now stationary pivot 8' to close the switch.

The switch operating mechanism so far described is illustrated in complete detail in my aforesaid Letters Patent, and the foregoing description is believed to be sufficient in order that the controlling mechanism therefor embodying my invention may be clearly understood.

For the purpose of maintaining the floating pivot 8' stationary under conditions in which the switch is to be closed, and to permit it to "float" when the switch is to be opened, there is provided electro-magnetically controlled means responsive to the magnitude of the current traversing the switch. To this end, the pivot 8' is connected through a link 16 to a bell crank 17 which is pivoted to the super structure 1' at 18. The other end of the bell crank is provided with a cam engaging face 19. It will be accordingly noted that clockwise movement of the bell crank 17 from the position illustrated causes the pivot 8' to be lowered and to assume a floating position so that the spring 12 may immediately open the switch.

For the purpose of restraining the bell crank 17 so that it serves under predetermined conditions to maintain the pivot 8' stationary, there is provided a holding member comprising a lever 20 pivoted at 21 and abutting at its free end the face 19 of the bell crank. As long as the holding member 20 is in the position illustrated the bell crank 17 is restrained from clockwise movement and the pivot 8' is maintained stationary. The holding lever 20 may be lifted out of engagement with the bell crank face 19 by an electro-magnet 22 coacting with an armature 23 secured to the holding member. An adjustable spring 24 serves to prevent attraction of the armature 23 and consequent clockwise rotation of the holding member 20 to free the bell crank until the electro-magnet 22 has been energized to a predetermined extent.

The electro-magnet 22 may be energized through a current transformer 25 connected in the line which is controlled by the switch structure 2-3. Likewise controlled by the electro-magnet is a tripping member 26 pivoted at 21 and having a camming edge 27 at its outer or free end. The tripping lever 26 is also provided with an armature 28 for coacting with the electro-magnet. In order that the invention may be more clearly illustrated,

the camming edge 27 as illustrated in Fig. 1, is spaced at an exaggerated distance from the end of the bell crank.

Referring now to Fig. 3, and assuming that the electro-magnet 22 is energized by an overload or short circuit of sufficient magnitude to attract the armature 23, it will be apparent that the actuation of the armature will occur at some part of the cycle, as at 30, where the current has rapidly risen to near its maximum value. Accordingly, the holding lever 20 is moved pwardly out of the path of the upper end of the bell crank, thereby permitting the same to move slightly in a clockwise direction to engage the camming face 27 of the tripping lever 26, as illustrated in Fig. 2. As the electro-magnet 22 is still strongly energized, the armature 28 on the tripping lever 26 is maintained in position and will restrain the bell crank 17 from further movement. As the current passes its maximum and approaches its subsequent minimum value of the cycle, the current will reach a value as at 31, at which value the electro-magnet 22 is no longer energized sufficiently to maintain the tripping lever 26 in a position restraining the bell crank lever. Accordingly, the spring 12 acting through the bell crank causes the free end of the bell crank engaging the cam face 27 to cam or move the tripping member upwardly and out of restraining engagement with the bell crank. The bell crank is thereupon instantly permitted to rotate in a clockwise direction under the influence of the spring 12 to cause rapid opening movement of the switch at, or near, the minimum value of the current traversing the same.

Resetting of the tripping mechanism is automatically accomplished during the closing operation of the switch mechanism during which the bell crank 17 is rotated counter-clockwise to the position illustrated in Fig. 1 so that the holding member 20 may slide into engagement with the face 19 under the influence of spring 24. The tripping lever 26 may be biased by gravity or other suitable means to a position where the cam face 27 is normally in the path of the bell crank.

It shall be understood that my invention is not limited to the specific type of switch closing mechanism associated therewith, and that modifications and changes in the specific structure and arrangement thereof will occur to those skilled in the art, without departing from the spirit of my invention.

What I claim as new and desire to secure by Letters Patent of the United States is:

1. In circuit interrupting apparatus comprising relatively movable contact structure, the combination of operating means, means normally biasing said operating means towards an open circuit position, and means for restraining said operating means in a closed circuit position, said restraining means be-

ing responsive to predetermined overload conditions for releasing the operating means so that the contacts are opened at, or near, the minimum value of the current traversing the same.

2. In circuit interrupting apparatus comprising relatively movable contact structure, the combination of operating means for opening and closing the contact structure, means normally biasing said structure towards open circuit position, and electro-magnetically controlled means for positively restraining the contact structure in closed position, said last named means being responsive to current conditions whereby the switch operating means are permitted to move under the influence of said biasing means to open circuit position during a minimum value of the current traversing the contact structure.

20 3. In circuit interrupting apparatus comprising relatively movable contact structure, the combination of operating means for said structure, means biasing said operating means towards open circuit position, electro-magnetic means responsive to the current traversing the contact structure, means controlled by said electro-magnetic means for initially releasing the operating means in response to a predetermined excess of current, and means 25 for subsequently releasing the operating means to cause opening movement of the contact structure during the subsequent part of a cycle in which the current is at a minimum.

4. In circuit interrupting apparatus comprising relatively movable contact structure, means normally biasing said contact structure towards open circuit position, means for restraining said contact structure in closed circuit position, and electro-magnetically controlled means for moving in response to excess current a restraining member normally maintaining the switch structure closed, and for subsequently restraining the said structure in closed circuit position until the current has substantially reached its minimum part of the cycle.

5. Circuit interrupting apparatus comprising in combination relatively movable contact structure, means biasing said structure towards open circuit position, holding means for restraining the contact structure in closed circuit position during normal current values, said holding means being actuated to release the contact structure in response to a predetermined excess of current, and latching means for further restraining the switch contact structure in closed position until the current has decreased to near its minimum value in the cycle.

60 6. Circuit interrupting apparatus comprising in combination relatively movable contact structure, means biasing said structure towards open circuit position, a member for restraining the contact structure in closed circuit position, and electro-magnetically

controlled means coacting with said restraining member comprising a holding member for preventing opening movement of the switch during normal current values, said holding member being moved out of engagement with the restraining member in response to predetermined excess of current, and tripping means for subsequently preventing opening movement of the contact structure until the current has decreased to near its minimum period in the cycle.

7. In circuit interrupting apparatus comprising relatively movable contacts, means controlling the opening movement of said contacts comprising a member normally holding the contacts in closed circuit position, electro-magnetically controlled means for releasing the holding member in response to a predetermined excess of current traversing the contacts, and means controlled by the electro-magnetic means for maintaining the contacts in closed position until the current has decreased to near its minimum value.

8. The combination with circuit interrupting apparatus comprising stationary and movable contacts and means for biasing the movable contacts towards its open circuit position, of means for controlling the opening movement of the movable contact comprising a holding member for restraining the movable contact in its closed position during normal current, electro-magnetic means for moving the holding member out of its restraining position in response to excessive current traversing the contacts, said holding member being actuated during the period in which the current is a maximum, and a second member for restraining the movable contact in its closed position independently of the aforesaid holding member by said electro-magnetic means, said second member being released to permit opening of the movable contact when the current has decreased to the subsequent minimum period of the cycle.

9. The combination with circuit interrupting apparatus comprising stationary and movable contacts and means for biasing the movable contact to its open circuit position, of means for controlling the opening movement of the movable contact comprising a rotatable member, and operative connection between said rotatable member and the movable contact whereby the rotatable member may be restrained so as to maintain the movable contact in closed position, a lever for normally engaging and restraining said rotatable member, an electro-magnet responsive to the current traversing the contacts for moving said lever out of its restraining engagement upon occurrence of excessive current, and a second lever adapted to be in restraining engagement with the rotatable member subsequent to actuation of the first lever, said second lever being controlled by said electro-magnet and arranged so that

the means for biasing the movable contact towards open position overcomes the restraining influence of the second lever during the period in which the current is a minimum.

5 In witness whereof, I have hereunto set my hand this 31st day of October, 1899.

CHARLES F. SCHWENNKER.
